Primary Examiner—Catherine Tuttle*(74) Attorney, Agent, or Firm*—Amy M. Fernandez(57) **CLAIM**

The ornamental design for a dispenser, as shown and described.

DESCRIPTION

FIG. 1 is a perspective view of the dispenser showing our design.

FIG. 2 is a front elevation view thereof.

FIG. 3 is a rear elevation view thereof.

FIG. 4 is a left side elevation view, the right side elevation view being a mirror image thereof.

FIG. 5 is a top plan view thereof; and,

FIG. 6 is a bottom plan view thereof.

The broken line showing of the interior of the bottom of the container is for illustrative purposes only and forms no part of the claimed design.
